Eugene, Oreg. 97405

Filed May 2, 1966, Ser. No. 2,114

Term of patent 14 years

(Cl. D71—1)

Fig. 2

FIG. 1 is a side perspective view, taken slightly from the front, of the convertible aeroplane and automobile with the wings and tail extended in flying position, embodying my new design;

FIG. 2 is a corresponding perspective view, taken slightly from the rear on the same side as FIG. 1;

FIG. 3 is a side perspective view, taken slightly from the front, as in FIG. 1 but showing the wings and tail folded up for ground surface travel.

I claim:

The ornamental design for a convertible aeroplane and automobile, substantially as shown and described.
